UNITED STATES PATENT OFFICE.

LOUIS NAGY, OF HAMILTON, ONTARIO, CANADA, ASSIGNOR OF ONE-HALF TO LASZLO MORTON, OF HAMILTON, CANADA.

GRAVITY TABLE.

Application filed May 24, 1926. Serial No. 111,117.

This invention relates generally to tables, the invention having more particular reference to a novel type of gravity table such as used on board ships and the like.

5 The invention has for an object the provision of an improved gravity table embodying adjustable features so as to render the device more effective.

10 A further object of the invention is the provision of an improved gravity table of novel construction and arrangement of parts.

15 For further comprehension of the invention, and of the objects and advantages thereof, reference will be had to the following description and accompanying drawing, and to the appended claims in which the various novel features of the invention are more particularly set forth.

20 Fig. 1, of the drawing, is a perspective view of my improved gravity table as it would appear when ready for use.

Fig. 2, is a side elevational view thereof.

25 Fig. 3, is a vertical sectional view, taken on the line 3—3 of Fig. 2.

Fig. 4, is a detail view, partly in section, 30 of the gravity member used in connection with my improved device.

Fig. 5, is a side elevational view of the gravity member.

35 Fig. 6, is an enlarged fragmentary detail view illustrating a modification of the gravity member.

Fig. 7, is a fragmentary side elevational view thereof.

35 As here embodied my improved gravity table comprises a table top 10, preferably circular, and having attached thereto, at its under side, a support 11, preferably circular of somewhat smaller diameter than the table 40 top 10, and provided with a recess 12, located at the common center of the support 11 and the table top 10, and adapted to receive the socket element 13, which is adapted to receive the ball element 14, of the center leg 15, provided with an enlarged lower extremity 16, having apertures 17, as a means 45 of suitably attaching the center leg 15 to the floor 18, deck or to any desired similar part of a ship or the like.

50 The above described construction is such as will permit the said table top 10, to be pivotally supported by the center leg 15. The support 11 has attached at its periphery a plurality of supporting rods 19, or the like, 55 depending downward therefrom, attached to

a supporting ring 20. The coil springs 21 are attached to the supporting ring 20, and to a base 22, adapted to be attached to the above mentioned floor 18.

The above described construction is such 60 as will permit the coil springs 21 to normally hold the table top 10 in a parallel position relative to the floor 18.

65 The gravity members comprise an upper member 23, having its upper extremity 24, formed or bent so as to form a hook, adapted to pivotally engage apertures 25 located in the supporting ring 20. The tubular member 26, is attached at its upper extremity to the lower extremity of the upper member 70 23, and extends downward therefrom. The supporting tube 26, is adapted to slidably engage the tubular member 26, and is provided with a thumb screw 27, threadedly attached thereto, and located at or near the 75 upper extremity of the supporting tube 26', so as to firmly hold the tubular member 26 in any desired extended position. The tubular member 26' is provided with an enlarged lower extremity 28, having a dovetailed recess 29, adapted to slidably receive the dovetailed member 30, having attached thereto, as at 31, a weight 32 preferably shaped similar to a plumb bob. The thumb screw 33, is threadedly attached to the enlarged lower 80 extremity 28, of the tubular member 26, so as to firmly hold the weight 32 in any desired extended position. The above described construction is such as will permit the weights 32 to be extended so as to hold 85 the table top 10 in a level position, when the above mentioned floor 18 is tilted or assumes an angular position, as may be the case on board ships or the like during a 90 rough sea or the like.

95 Referring in particular to Figs. 6 and 7, of the accompanying drawing, in which I have illustrated a modification of my improved device the upper member 23 has threadedly attached thereto, a thumb screw 100 34. It is understood that the thumb screw 34 is positioned so as to permit its extremity 35 to engage the supporting ring 20, and extend, swing or pivot the weight 32, and firmly hold the said weight 32 in 105 the above mentioned position, so as to hold the table top 10 in a level position, when the above mentioned floor is tilted as above set forth.

Having thus described my invention, 110

what I claim as new, and desire to protect by Letters Patent of the United States, is as follows:—

1. In a gravity table of the class described, a table top having attached thereto, a support provided with a recess located at the common center of the said support and the said table top, and adapted to receive a socket element, adapted to receive the ball 10 element of a center leg provided with an enlarged lower extremity provided with a suitable means of attaching same to the floor of a ship or the like, so as to permit the said table top to be pivotally supported 15 by the said center leg, said support having attached at its periphery a plurality of supporting rods, depending downward therefrom and attached to a supporting ring, coil springs attached to the said supporting 20 ring, and to bases, adapted to be attached to the said floor, so as to permit the said coil springs to normally hold the said table top in a parallel position relative to the said floor.
- 25 2. In a gravity table of the class described, a table top having attached thereto, a support provided with a recess located at the common center of the said support and the said table top and adapted to receive a socket element, adapted to receive the ball 30 element of a center leg provided with an enlarged lower extremity provided with a suitable means of attaching same to the floor of a ship or the like so as to permit the said table top to be pivotally supported 35 by the said center leg, said support having attached at its periphery a plurality of supporting rods, depending downward therefrom, and attached to a supporting ring, coil springs attached to the said supporting 40 ring, and to bases, adapted to be attached to the said floor, so as to permit the said coil springs to normally hold the said table top in a parallel position relative to the said floor.
- 45 3. In a gravity table of the class described, a table top having attached thereto, a support, said support having attached at its periphery a plurality of supporting rods, depending downward therefrom, and attached to a supporting ring, coil springs 50 attached to the said supporting ring and to bases, adapted to be attached to the said floor, so as to firmly hold the weight in any desired extended position, so as to permit the weights to be extended so as to hold the 55 said table top in a level position when the above mentioned floor is tilted, said supporting ring provided with an enlarged lower extremity having a dovetailed recess adapted to slidably receive a dovetailed 60 member having attached thereto a weight, a thumb screw threadedly attached to the said enlarged lower extremity of the said tubular member.
3. In a gravity table of the class de- 70 scribed, a table top having attached thereto a support, said support having attached at its periphery a plurality of supporting rods, depending downward therefrom, and attached to a supporting ring, coil springs 75 attached to the said supporting ring and to bases, adapted to be attached to the said floor, so as to permit the said coil springs to normally hold the said table top in a parallel position relative to the said floor.
4. In a device of the class described, a table top, a support attached thereto, the support being formed with a recess located at the common center of the table top and support, a central leg having at the upper end a ball element flexibly connected to the said recess, a plurality of supporting rods attached to the periphery of the support, and depending downwards therefrom, a supporting ring attached to the lower ends 85 of the supporting rods, coil springs attached to the supporting ring, and bases attached to the lower ends of the coil springs.

In testimony whereof I have affixed my 95 signature.

LOUIS NAGY.
